MACHINE FOR VENDING ARTICLES
STOCKED IN A PLURALITY OF
CHUTES

Louis Steiner, New York, N. Y.

Application July 29, 1938, Serial No. 221,927

7 Claims. (Cl. 194—57)

This invention relates to machines for vending articles stocked in a plurality of chutes. It is particularly directed to coin regulated mechanism for controlling the dispensing of articles from said chutes.

An object of this invention is to provide a machine of the character described, from which articles may be dispensed by insertion into the coin chutes of the machine, different amounts of money, whereby articles in some of the chutes may be vended at one price and articles in other chutes at another price, while employing a single coin mechanism, the construction being such that any of the chutes may be arranged to vend articles either at one price or the other.

A further object of this invention is to provide a neat, compact, rugged and durable device of the character described, which shall be relatively inexpensive to manufacture, smooth and positive in operation, easy to adjust and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front, elevational view of part of a vending machine embodying the invention, and showing the coin regulated mechanism before any draw bar is pulled;

Fig. 2 is a view similar to Fig. 1, with the coin controlled levers removed;

Fig. 3 is a cross-sectional view taken on line 3—3 of Fig. 1;

Fig. 4 is a cross-sectional view taken on line 4—4 of Fig. 3;

Fig. 5 is a cross-sectional view taken on line 5—5 of Fig. 3, with one of the draw-bars pulled forwardly;

Fig. 6 is an enlarged, detailed view of the mechanism for permitting articles in some of the chutes to be vended at one coin less than other chutes (fifteen cents);

Fig. 7 is a view similar to Fig. 1 but showing the position of the coin regulated means when a dime and nickel are inserted and a draw bar is pulled to dispense a fifteen cent package; and

Fig. 8 is a view similar to Fig. 7 but showing the levers in still another position, when four

nickels are inserted into the machine and a draw bar pulled to dispense a twenty cent package.

Referring now in detail to the drawings, 10 designates a vending machine embodying the invention. The vending machine comprises an outer casing not shown, within which is mounted a box 11 having a bottom wall 12, side walls 13, a rear wall 14. On said bottom wall 12 is a curved wall 15 extending upwardly to the rear wall 14 and forming a dispensing chamber 19. 10

At the front of box 11 is a front wall 17 having an opening 18 at the bottom, communicating with the dispensing chamber 19 at the bottom of the box. Fixed within the box 11 is a member 20 having a horizontal wall 21 extending from the front wall 17 rearwardly. Extending downwardly from wall 21 is a wall 22, parallel to the rear wall 14, and extending from wall 22 is a forwardly and downwardly inclined wall 23. Extending upwardly from wall 21 is a wall 24, 20 aligned with the front wall 17 and formed with a plurality of parallel, spaced openings 25, for the purpose hereinafter appearing. Mounted on wall 21 is a row of vertical aligned chutes 26 in which packages 27 of cigarettes or other articles to be vended are stacked.

Means is provided to dispense the packages 27 from the chutes 26 into chamber 19. To this end, wall 21 of member 20 is formed with a plurality of parallel slots 30 aligned with the slots 25. 30

Slidably mounted on wall 21 are a plurality of parallel draw bars 31 passing through the openings 25 and projecting from the front of the machine. The lower edge of each draw bar 31 is slidably received within a slot 30. At the rear end of each draw bar is a downwardly projecting thickened hook portion 33, contacting the underside of wall 21. The rear end of each draw bar is also formed with a widened portion 34, contacting the upper side of plate 21, and normally disposed within the lower end of one of the chutes. When any draw bar 31 is drawn forwardly, a package of cigarettes within said chute and resting on the widened portion 34 of the bar, will drop downwardly onto the wall 21. 45

The rear walls of the chutes are formed with cut-outs, so that when the bar 31 is again moved rearwardly, in the manner hereinafter explained, it will push the lowermost package through the cut-out, onto the curved wall 15, into the dispensing chamber 19. 50

Means is provided for returning the draw bar to its rearward position after the bar has been pulled forwardly. To this end, there is fixed to the inner side of side walls 13 of box 11, reinforce-

ing plates 37. Plates 37 and side walls 13 are formed with aligned registering openings 38, in which are journaled the outer ends of a transverse horizontal shaft 39. At one side of the box, 5 contacting walls 13 and 37 are formed with registering arcuate slots 40 having centers of curvature at the axis of shaft 39.

Fixed to the shaft 39 adjacent the inner sides of the walls 13 and 37, are arms 41 carrying at 10 the outer ends a transverse horizontal rod 42. Fixed to one of the arms 41 is a horizontal stud shaft 43, projecting through the slots 40.

Mounted on the shaft 39 are a pair of spaced torsion springs 45, each having an arm 46 contacting the inner side of front wall 17, and a second arm 47, contacting the rod 42. The hook portions 33 of the draw bars 31 are adapted to engage the rod 42. When any draw bar is pulled forwardly, the rod 42 will also be pulled forwardly 20 to tension the springs 45, the latter serving to return the draw bar and the rod 42 to their normal rearward position when the draw bar is released.

To prevent access to the lower ends of the 25 chutes through the chamber 19, when the draw bar is pulled forwardly, there is pivoted to the side walls 13, a transverse shaft 50 carrying a plate 51, and connected by links 52 to the stud shaft 43. When a draw bar is pulled forwardly, 30 the links 52 swing the plate 51 downwardly to cover the cut-outs at the lower ends of the chutes 26.

Means is provided to prevent more than one draw bar at a time from being pulled forwardly. 35 To this end, there is pivoted to the underside of wall 21, as by a vertical pivot pin 55, a horizontal plate 56 contacting the underside of wall 21 and disposed between each pair of adjacent draw bars. The forward ends of the plates 56 40 may be supported by lips 57, punched downwardly from the wall 21 to form openings 58 above the locking plates. The total clearance between all of the locking plates 56 is sufficient to permit only one draw bar to be pulled forwardly. When a 45 bar is drawn forwardly, the portion 33 thereof moves between the locking plates on opposite sides thereof, causing the locking plates to move into contact so as to prevent any other draw bar from being pulled forwardly, until the first draw bar is released.

Means is provided to vend articles in the chutes 26 at two different prices while employing a single coin controlled mechanism for controlling the draw bars 31. For the purpose of illustration, 55 the drawings disclose mechanism to permit the packages in the first two chutes 26 to be vended upon insertion of a dime and a nickel into the machine, and the articles in the last three chutes to be vended upon insertion of either a dime and 60 two nickels or four nickels into the machine, whereby the machine will vend 15¢ packages of cigarettes as well as 20¢ packages of cigarettes.

To this end, there is fixed to the outer side of one of the side walls 13 of the box, a vertical 65 plate 60, formed on the outer faces thereof with an L-shaped groove 62, in which is slidably mounted a slide plate 63 held within said groove by a pair of vertical, spaced, front and rear plates 64, 64a, screwed to the plate 60 as by screws 65, 70 65a.

Plate 60 is formed with a horizontal slot 66, and walls 13 and 37 are formed with horizontal 75 registering slots 68, aligned with said slots 66. Fixed to the plate 63 and projecting through slots 66 and 68 into chamber 19 is a stud shaft

69. Said shaft 69 is connected by a link 70 to the adjacent arm 41.

It will now be understood that upon drawing any of the draw bars forwardly, the slide member 63 will be caused to slidably move forwardly 5 within its groove 62. Slide plate 63 is formed, adjacent the rear end thereof, with a horizontal slot 72 having a widened portion 73 at the front forming a shoulder or ledge 74. At the forward end of slide plate 63 are horizontal slots 75 and 10 76 formed with widened downwardly extending portions 77 and 78, respectively, forming ledges 79 and 80. Slide plate 63 is furthermore formed with a vertical central coin slot 82, below the horizontal slot 72, and with a coin slot 83 aligned 15 with said first slot and disposed above the slot 72.

Fixed to the plate 60 and aligned therewith is a vertical upwardly extending plate 85. Plate 85 is formed with a slot 86, registering with and extending upwardly from the slot 83. The slot 86 extends to the front of the machine where a coin, such as a dime, may be inserted, which will drop down through the slots 86 and 83 into the slot 82.

Slide plate 63 is furthermore formed with a 25 vertical central coin slot 90, extending downwardly from the slot portion 75 and with a slot 91 aligned with slot 90 and extending between the slots 75 and 76, and with a slot 92 aligned with a through slot 91 extending upwardly above the 30 slot 76.

Plate 85 is formed with a slot 93 aligned with the slot 92, so that a coin, such as a nickel, inserted into the coin chute or slot 93, will drop to the bottom of slot 90. Slidably mounted on plate 60, beneath the slide plate 63, is a horizontal bar 135, the forward end of which projects from the front of the machine. A coil tension spring 136 interconnecting the bar with the plate 64 normally pulls the bar forwardly. Said 40 bar covers the lower ends of the slots 82 and 90. When the bar is pushed rearwardly, whatever coins which are in the slots 102 or 90, 91, 92, drop down through the return chutes 137 to the dispensing chamber 19. The bar 135 may 45 be pushed when the purchaser desires to have the coins returned if he has not already pulled a draw bar to get a package of cigarettes.

As shown in Fig. 2 of the drawings, a coin inserted into the slot 86 will drop onto bar 135 and 50 will project into the widened portion 73 of slot 72 and cover the ledge 74 so as to be substantially tangent to the lower edge of the rear portion of slot 72.

A coin placed in coin chute 93 will drop to 55 slot 90 onto bar 135 and will project into the widened portion 77 of slot 75 and cover the ledge 79, so as to be substantially tangent to the rear portion of slot 75. If a second coin is inserted 60 into the slot 93, it will drop to the slot 91 so as to rest on the first coin, and in such position, project into widened portion 78 of slot 76, to 65 cover ledge 80 and be substantially tangent to the bottom edge of the rear portion of slot 76.

Pivoted at the forward end thereof to the plate 64, as on pivot 100, is a lever 101 having a horizontal projection or tab 102, projecting into the widened or forward portion 73 of the slot 72. A coil tension spring 104 interconnects the lever 101 with the plate 64a to keep the tab 102 in 70 horizontal alignment with the shoulder 74. Lever 101 may be formed with a slot 105; and a headed screw 106 screwed to plate 64a and passing through said slot, serves to guide the lever for pivotal movement about the pin 100.

Pivoted to the plate 64a, as at 110, and disposed above and in the plane of lever 101, is a lever 112, formed with a slot 113 receiving a headed guide screw screwed to plate 64. Lever

5 112 is provided with a tab or projection 115 extending into the lower widened portion 77 of the slot 75, normally being held at the level of the shoulder 79 by a coil tension spring 116, interconnecting the free end of lever 112 with the 10 fulcrumed end of lever 101.

Pivoted to the plate 64a, as at 119, and disposed in the plane of the levers 101 and 112, is a third lever 120, formed with a slot 121 receiving a headed screw 122, screwed to the plate 64. Lever 15 120 is formed with a tab 125 projecting into the widened portion 78 of the slot 76, and normally held at the level of the shoulder 80 by a coil tension spring 126 interconnecting the outer end of said lever with the screw 114.

20 There is also pivoted to the plate 64a, as at 127, a fourth lever 128, formed with a slot 129 to receive a headed screw 130, screwed to the plate 64. The lever 128 is formed with a horizontal tab 133 disposed above the upper edge of the plate 63 and in alignment with the projections 115 and 125 of the levers 112 and 120.

It will be noted that the vertical distance between the upper edge of bar 135 and the projection 102 on the lever 101, is less than the vertical 30 distance between the upper edge of said bar and the projection 100 on the lever 112, the reason being that the chute 86 and the slots 82, 83 are for dimes, whereas the chute 93 and the slots 90, 91, 92 are for nickels.

35 When a dime is inserted into the chute 86, it drops to the bottom of the slot 82 and covers the shoulder 74, so that upon pulling a draw bar forwardly, the upward portion of the coin serves as a ramp engaging the projection 102 to lift 40 the lever 101 above the shoulder 74.

When a nickel is inserted into the chute 93, it drops to the bottom of the slot 90 to cover the shoulder 79 and serves as a ramp engaging the projection 115 of the lever 112, for lifting said 45 lever when a draw bar is pulled forwardly. A second nickel dropped in the chute 93 drops to the bottom of slot 91 to rest on the first nickel, and when a draw bar is pulled forwardly, the second nickel engages the projection 125 to serve 50 as a ramp for lifting the lever 120.

It will now be understood that when a dime and two nickels are inserted into the machine, levers 101, 112 and 120 are lifted when a draw bar is pulled to permit the draw bar to be pulled, for 55 dispensing a package of cigarettes. The machine will operate when four nickels are inserted into the chute 93. The first two nickels will serve to lift the levers 112 and 120. The third nickel rests on the second nickel and merely serves as 60 a spacer for the fourth nickel, which rests on top of the third nickel. The fourth nickel serves as a ramp to lift the fourth lever 128. The lever 128 is interconnected to the lever 101 by link 140. When the lever 128 is lifted therefore, the lever 65 101 is also lifted to move the projection 102 above the shoulder 74. Thus, when four nickels are inserted into the chute 93, a draw bar may be pulled forwardly as the projections 102, 115 and 125 will be raised to clear the shoulders 74, 79 and 80.

70 When a draw bar is pulled forwardly, the coins are moved to the right until they are aligned with the chutes 141 leading to a coin box, and hence drop into the coin box.

75 Any suitable means (not shown) may be pro-

vided to prevent the slide 135 from moving back to its normal position, until a draw bar has been pulled forwardly sufficiently for the coins to drop into the coin box.

Means (not shown) may also be provided for preventing the slide from returning to normal position after a draw bar has been pulled forwardly, unless the draw bar has been pulled forwardly sufficiently for the coins to drop through the coin chutes 131 to the coin box.

It will now be understood that the mechanism described above permits packages to be dispensed from the chutes upon insertion of 20¢, either in the form of a dime and two nickels, or four nickels. It is often desirable to stock some of the chutes 26 with 15¢ packages of cigarettes. Means is therefore provided to permit packages from any of the chutes to be dispensed for 15¢, that is, by insertion of only one dime and one nickel into the machine.

To this end, there is fixed to the outer end of the lever 120, a vertical plate 150, having a rearward projection 151.

Attached to the locking plate 56, at the right of each of the chutes containing the 15¢ cigarettes, and extending through openings 58 in wall 21, is an upstanding member 155, carrying at its upper end a horizontal pin 156, supporting a pair of spaced, parallel washers 157, separated by a collar 158 received on said pin. In the drawings, 30 the first two chutes 26 are shown for the purpose of illustration, to contain the 15¢ packages of cigarettes, and hence, two of the locking plates at the right of the first two chutes are provided with upstanding members 155.

Slidably mounted on the pins 156, and disposed between the washers 157, is a cross-piece 160 having longitudinal slots 161 to receive said pins. The cross-piece 160 extends to one end of the machine, as at 162. Pivoted to the end 162 of member 160, is a lever 163. The lever 163 is pivoted, as at 164, to the plate 60, and is provided with a toe 165 engaged beneath the projection 151 of the plate 150.

It will be noted that the pins 158 are normally 45 at the right ends of the slots 161. When any of the draw bars, other than the first two bars, are pulled forwardly, all of the locking plates on the left of said draw bar are pivotally moved to the left, thus moving the pins 158 to the left 50 within the slots 161 without affecting member 160. A dime and two nickels or four nickels must be inserted into the machine to operate any of the draw-bars, except the first two.

When only one nickel and one dime are inserted into the machine, and one of the first two draw bars are drawn, the dime serves to lift the lever 101, and the nickel serves to lift the lever 112. Upon drawing one of the first two draw bars forwardly, either one or both of the locking plates 60 at the right of the first two draw bars will be swung to the right, to lift the toe 165 to raise member 150, and hence lift the lever 120, for bringing the tab or projection 125 thereof above the shoulder 80. Thus, the shoulders 74, 79 and 80 of the slide plate are cleared to permit a package to be dispensed from either of the first two chutes, upon insertion into the machine of a dime and nickel.

It will now be understood that the machine 70 may be arranged to permit packages from any of the chutes to be vended for a dime and nickel. This may be done by merely fixing to the locking plate on the right of the chute with the 15¢ cigarettes, an upstanding member 155 and extending 75

the cross-piece 160 to the pin 156 on said up-standing member.

Although this invention has been described in relation to a 15¢ and 20¢ dispensing device, it 5 will be understood that any other coins may be inserted for the dime and nickels described herein. Furthermore, packages other than cigarettes may be dispensed with the improved machine.

It will be further understood that the machine 10 described herein may be converted to sell only 15¢ cigarettes. This may be done by omitting the top lever 128, interconnecting the link 140 to the lever 120, instead of to the lever 128, and providing a tab on the lever 120 above the tab 125 to 15 be engaged by a third nickel, whereby the cigarettes may be dispensed either by insertion of a dime and a nickel or three nickels into the machine. Such a construction is disclosed in my Patent No. 2,083,928, issued June 15, 1937. The 20 15¢ machine such as disclosed in my said patent may be converted to permit one or more of the chutes to dispense 10¢ packages upon insertion into the machine of a dime only, by attaching the member 150 to the second lever from the 25 bottom (lever 112 in this application) and fixing to the locking plates on the right of each of the 10¢ chutes, a member 155 cooperating with a cross-member 160 and pivoted lifting lever 163.

It will thus be seen that there is provided a 30 device in which the several objects of this invention are achieved, and which is well adapted to meet the conditions of practical use.

As various possible embodiments might be made of the above invention, and as various changes 35 might be made in the embodiment above set forth, it is to be understood that all matter herein set forth or shown in the accompanying drawings is to be interpreted as illustrative and not in a limiting sense.

40 Having thus described my invention, I claim as new and desire to secure by Letters Patent:

1. In a vending machine, a plurality of reciprocable draw bars for dispensing articles from chutes, coin controlled means to lock said draw 45 bars against movement, said means including a movable member, means for moving said member upon pulling any of the draw bars, a plurality of locking members engaging said movable member to hold the same against movement, and 50 hence prevent any draw bar from being pulled, means to move said locking members out of locking position relative to said movable member, upon insertion of a plurality of coins into the machine, and pulling any of the draw bars forwardly to permit said movable member to be 55 moved, and means operatively connected to a group of one or more of said draw-bars, to move one of said locking members out of locking position, whereby to permit said movable member to 60 be moved upon pulling one of said group of draw bars, after insertion into the machine of said plurality of coins, less one coin, necessary to move said one of said locking member.

2. In a vending machine, a support, a plate 65 slidably mounted thereon and formed with a shoulder, a lever pivoted to said support and having a projection aligned with said shoulder to prevent movement of said slide plate in one direction, said plate having means to receive a coin 70 adapted to cover said shoulder and serve as a ramp engaging said projection to pivotally move the lever and lift said projection over said shoulder as the plate is slidably moved, to permit movement of said slide plate in said direction, 75 a member adapted to move articles out of a

chute, means interconnecting said member with said slide plate to move said slide plate in said direction when said coin is within said receiving means, a second member adapted to move articles out of another chute, and means operatively 5 connected with said second member to move said lever to bring said projection out of alignment with said shoulder whereby to permit said slide plate to be moved, upon moving said second member, without said coin being within said receiving 10 means.

3. In a vending machine, a draw bar adapted to be pulled forwardly by the purchaser, a member movably mounted on said machine, a transverse rod within said machine connected to said 15 movable member and adapted to move the same back and forth, means on said draw bars to engage said rod and pull the same forwardly when any of said bars are pulled forwardly, for moving said movably mounted member forwardly, 20 spring means engaging said rod to move the same rearwardly after a draw bar has been pulled forwardly and released, to move said movably mounted member rearwardly said movably mounted member being formed with a shoulder, 25 means adapted to engage said shoulder to prevent forward movement of said movably mounted member, and hence preventing any draw bar from being pulled, means to receive a coin in said machine, in such position as to cover said shoulder, 30 whereby to move said means out of alignment with respect to said shoulder when a draw bar is pulled forwardly, and means controlled by one or more of said draw bars to move said means out of alignment relative to said shoulder when 35 any of said one or more draw bars are pulled forwardly, even when said coin is not within said receiving means.

4. In a vending machine, a plurality of draw bars parallel to each other, means to prevent more than one draw bar at a time from being pulled forwardly, said means comprising locking plates pivoted to the machine and interposed between said draw bars, each of said draw bars having a portion adapted to move between a pair 45 of adjacent locking plates on opposite sides thereof, when said draw bar is pulled forwardly, a slide plate mounted on said machine and adapted to move forwardly and rearwardly, means to move said sliding plate forwardly, when any draw bar is pulled forwardly, a lever pivoted to said machine and having a portion engaging a portion 50 of said slide plate, to prevent said slide plate from being moved forwardly, said lever being adapted to be lifted by a coin inserted into the 55 machine to bring said portion thereof out of engagement with respect to said slide plate to permit a draw bar to be moved forwardly, and means connected with one or more of said locking plates adapted to move said lever out of engagement 60 with respect to said slide plate when any of certain of said draw bars are pulled forwardly.

5. In a vending machine, a plurality of draw bars parallel to one another, a plurality of locking plates between said draw bars, to prevent 65 more than one draw bar at a time from being pulled forwardly, a slide plate on said machine, means to pull said slide plate forwardly when any draw bar is pulled forwardly, said slide plate having a shoulder, a lever pivoted to said machine and having a portion aligned with said shoulder, a member attached to one of said locking plates, and means on said member for rotating 70 said lever when said locking plate is moved in one direction, upon drawing one of said draw 75

bars forwardly, to bring said projection out of alignment with said shoulder and permit said slide plate to be moved forwardly by said draw bar.

5 6. In a vending machine, a plurality of draw bars parallel to one another, a plurality of locking plates between said draw bars to prevent more than one draw bar at a time from being pulled forwardly, a slide plate on said machine, means 10 for pulling said slide plate forwardly when any draw bar is pulled forwardly, said slide plate having a shoulder, a lever pivoted to said machine and having a portion aligned with said shoulder to prevent movement of said slide plate, and 15 hence to prevent any draw bar from being pulled forwardly, said slide plate being provided with means to receive a coin, and said lever being adapted to be lifted by a coin within said coin receiving means to bring said portion thereof out 20 of engagement with the shoulder on the slide plate, to permit a draw bar to be moved forwardly, a member fixed to one of the locking plates and extending upwardly therefrom, a transverse member mounted on said upstanding member and having a lost motion connection therewith, a member pivoted to said machine and to said last member and having a projecting finger, and a member attached to said lever and having a projection disposed above said finger, whereby when a draw bar on one side of said locking plate is pulled forwardly, it will not move the transverse member, and a coin will be required to be deposited into said coin receiving

means to permit said draw bar to be pulled forwardly, and whereby when a draw bar on the other side of said locking member is pulled forwardly, it will move the locking member and also the transverse member to cause pivotal movement of the member pivoted to the machine and to the transverse member, thereby causing the finger to lift the member which is connected to the lever for lifting the lever and permitting said last mentioned draw bar to be pulled forwardly with- 10 out deposit of a coin in said coin receiving means. 15 7. In a vending machine, a plurality of parallel draw bars adapted to eject articles from chutes, locking plates between said draw bars to prevent more than one draw bar from being pulled forward at a time, a slide plate slidably mounted on the machine, means for sliding the slide plate forwardly when any draw bar is pulled forwardly, a shoulder on said slide plate, a lever pivoted to the machine, means on said lever to engage the 20 shoulder of said slide plate to prevent the slide plate from being drawn forwardly, said slide plate being formed with coin receiving means, said lever being adapted to be lifted to release said slide plate by a coin within said coin receiving means, a transverse member having a pin 25 and slot connection with one or more of the locking plates, and means connected to said transverse member to lift said lever when said transverse member is moved by the locking plates hav- 30 ing a pin and slot connection therewith.

LOUIS STEINER.
